UNITED STATES PATENT OFFICE.

ERNEST HAUSBERG, OF CHARLES CITY, IOWA.

ELECTRICALLY-OPERATED TYPE-WRITER.

1,209,961.

Specification of Letters Patent.

Patented Dec. 26, 1916.

Application filed July 25, 1912. Serial No. 711,602.

To all whom it may concern:

Be it known that I, ERNEST HAUSBERG, a citizen of the United States, and a resident of Charles City, in the county of Floyd and State of Iowa, have invented a new and useful Electrically-Operated Type-Writer, of which the following is a specification.

My invention relates to that class of electrically operated typewriters in which, by the depression of a key, a selective magnet is energized to thereby move a type bar operating device to position for printing, and immediately thereafter the power magnet is energized for the purpose of bringing the selected type bar to printing position.

The object of my invention is, broadly, to provide an electrically operated typewriter of this class in which the number, size and weight of the mechanically operated parts of the machine are reduced to a minimum, and practically all of the elements are electrically operated, to thereby insure great speed, ease and certainty of operation of the machine, reduce to a minimum the noise attendant upon its operation and the wear upon the wearing parts; and also in this connection, to reduce the expense of manufacture and cost of maintenance of machines of this class.

More specifically, it is my object to provide an electrically operated device of simple, durable and inexpensive construction, to be energized at the same time that a selective magnet is energized, for the purpose of operating a switch designed to close the circuit of the power magnet and to keep it closed until it is automatically opened upon the completion, or during the progress, of the type bar stroke, thus insuring a full type bar stroke even through the contact at the key be not long enough to fully energize the power magnet, and providing for a return of the type bar even through the contact at the key continues.

A further object is to provide improved means of simple, durable and inexpensive construction, to be operated by the selective magnets for connecting the type bar operating levers with the universal operating bar

that is connected to the power armature, and also to provide an improved arrangement of the selective magnets and their armatures, whereby they may be readily and easily assembled or disconnected.

A further object is to provide an improved arrangement of the type bar operating devices especially designed for use with type bars arranged for visible printing in connection with a series of selective magnets, whereby all of the type bars proper may be made identical in shape and arranged in the usual semi-circular form to strike upon a common printing center on the platen and at the same time to provide for moving each of the type bars through the necessary length of movement required for striking the platen, while having all of the type bars operated from a single power armature having exactly the same length of movement each time that it is actuated.

My invention consists in certain details, in the construction, arrangement and combination of the various parts of the device, whereby the objects contemplated are attained, as hereinafter more fully set forth, pointed out in my claims and illustrated in the accompanying drawings in which:

Figure 1 shows a side elevation of a typewriter embodying my invention, a part of the typewriter frame being broken away to show the internal construction. Fig. 2 illustrates, diagrammatically, the electrical features embodied in my invention. Fig. 3 shows a central, vertical, longitudinal sectional view of the rear portion of my improved typewriter with the carriage omitted. Fig. 4 shows an enlarged detail view of the electric switch device for making and breaking the circuit of the power magnet. In this view the circuit making and breaking device is shown in its closed position. Fig. 5 shows a front elevation of the spring actuated switch device, illustrated in Fig. 4, and its support. Fig. 6 shows a detail sectional view on the line 6—6 of Fig. 3. Fig. 7 shows a vertical, transverse, sectional view of a typewriter embodying my invention, the portion at the right of said figure being

taken on the dotted line *a—a* of Fig. 3, and the portion at the left, on the dotted line *b—b* of Fig. 3.

- Referring to the accompanying drawings, 5 I have used the reference numeral 10 to indicate generally the frame of the typewriter. On this frame is a sliding carriage 11 of ordinary construction containing the platen 12. The carriage is provided with an ordinary 10 spacing mechanism illustrated generally by the reference numeral 13, which spacing mechanism is automatically operated in a manner to be hereinafter more fully described.
- 15 Mounted in the front of the typewriter frame is a series of keys 14, each of which rests upon a spring 15 which, when depressed, engages an electrical conducting bar 16 and closes an electric circuit from said 20 bar through the depressed spring.

Mounted upon the frame in semi-circular arrangement below the platen is a series of type bars 17, pivotally supported on a curved shaft 18, and each provided with an upwardly projecting lug, 19. Immediately in the rear of and below the shaft 18 is another shaft 20 extending across the machine, and pivoted to this shaft 20 is a series of levers 21, one for each type bar, those in the 25 center being shorter than those at the ends, as may be seen by comparing the central one, shown in Fig. 3, with the end one shown in Fig. 1. The levers 21, adjacent to the ends, have their upper portions inclined upwardly 30 and inwardly in a direction toward the printing center of the platen and at the upper end of each of the levers 21 is a link 22 to connect it with the corresponding lug 19.

Arranged near the bottom of the typewriter frame and extended transversely 40 across the frame, is a bearing shaft 23 to which is pivoted a series of levers 24, one for each of the levers 21. These levers 24 vary in length; those at the ends being longer 45 than the ones at the center, as clearly shown in Fig. 7. At the upper end of each of the levers 24 is a link 25 connecting it with the corresponding lever 21. The links 25 that connect to the central levers 21 are attached 50 to the levers 21 near their lower ends, while the links 25 that are connected to the outer levers 21 are connected thereto near their upper ends, as shown in Fig. 1. The arrangement is such that if any one of the levers 24 55 is moved a certain distance rearwardly at its upper portion, the corresponding type bar will be moved a sufficient distance to strike upon the printing center of the platen, and this is done by means of type bars that are 60 all of the same size and shape, and that may be made from the same set of dies.

It is obviously a comparatively easy and inexpensive matter to cut the levers 21 and 24 to different lengths and to connect the

links 25 thereto at different points, as required to produce the desired result in operating the type bars by means of comparatively slight movements, all of the same length, applied to the levers 24.

In the following description and claims, 70 the term "type bar operating devices" is intended to include the levers 21 and 24 and the links for connecting them with each other, and with the type bars, or any equivalent construction.

75 My improved means for operating a type bar upon the depression of a key, comprises a series of selective magnets 26. This series is arranged in two rows extended transversely across the machine on opposite sides 80 of the shaft 23, each row being attached to a supporting bar 27, and these selective magnets are electrically connected, one with each of the springs 15 of the keys, as will appear on the electric diagram shown in Fig. 2. Extended across the machine frame in front of the front row of magnets 26 is a shaft 28, and a similar shaft 29 is extended across the machine in the rear of the rear row of magnets 26. Pivoted to the shafts 28 and 29 are 90 the levers 30 which extend toward each other with their ends in overlapping position. These levers 30 are arranged alternately, and each of them is provided with an armature 31 designed to coat with the adjacent 95 magnet 26. Pivoted to the inner end of each lever 30 is a rod or link 32 extended upwardly and connected to a lever 33 pivoted to the adjacent lever 24 at about the central portion of said lever 24. This point of connection will however, vary according to the lengths of the levers 24, being farther from the tops of the levers positioned at the sides of the machine, and somewhat nearer the tops of those levers at the middle of the machine. On the rear end of the lever 33 is a hook 34, and at the front end of the lever 33 is a contractible coil spring 35, the other end of which is connected to a pin 36 on the lever 24, which spring normally holds the 105 hook 34, its rod 32 and the corresponding lever 30 in an elevated position with the armature 31 above and out of contact with its magnet. The parts are so arranged that when the selective armature has been attracted to its magnet the lower pivotal point of said rod or link 32 will closely approach the pivotal point of the lever 24, so that said lever and said rod or link may move backwardly and forwardly at their upper ends to 110 the limited extent required in use, without moving the selective armature or its lever 30. 115 Pivoted connected to the shaft 23 are the arms 37 which are fixed at their upper ends to the universal operating bar 38. The upper end of this bar is beveled or inclined at 39 to coat with the beveled ends of the hook 34. Means are provided, as will herein- 120 125

after appear, for moving this universal operating bar rearwardly by means of the power magnet hereinafter described, and it is returned to its forwardly extended or 5 normal position by means of the spring 40.

Some of the advantages of the construction and arrangement of the means for connecting the levers 24 with the universal operating bar are that the arrangement is 10 of extremely simple and inexpensive construction and easy to construct and assemble. Furthermore, the size and weight of the mechanically operated parts are reduced to a minimum in that when any selective 15 magnet is energized, its corresponding lever 30 is moved downwardly only a slight distance, and this moves the small lever 33 downwardly far enough to connect the hook 34 with the universal operating bar. 20 Then when the universal operating bar moves rearwardly the lever 24 and the type bar operating mechanism are actuated. Obviously, there is substantially no noise occasioned by the operation of these parts 25 and the selective magnets may be made very small and may be operated by a comparatively slight electric current, for the reason that the size and weight of the parts they operate are very slight.

30 In order for any type bar operating device to be actuated, it is necessary that the power magnet be energized. For this purpose a switch mechanism is provided which is actuated by a magnet in circuit with each 35 of the selective magnets. This switch mechanism closes the circuit through the power magnet. All of the necessary operations for printing are made, therefore, upon the completion of a single electrical contact at 40 a key. A novel and advantageous feature of my invention, however, is that the switch mechanism is so constructed that it automatically breaks the circuit of the power magnet upon the rearward movement of 45 the power armature, thus allowing the type bar to be returned to normal position without any release of the contact at the key and without any mechanical disconnecting of the parts. Another important feature 50 is that the switch mechanism having closed the circuit of the power magnet, this circuit will remain closed irrespective of the continuance of the key contact, thus insuring a full stroke of the type bar.

55 My improved switch device comprises a single electromagnet 41 fixed to a support 42 and arranged in a circuit in series with all of the selective magnets, as shown on the diagram in Fig. 2, so that this magnet 60 is energized substantially at the same time as the selected one of the magnets 26. Fixed to the support 42 which is attached to the frame, is an arched spring 43 having an arm 44 fixed to its free end and ex-

tended downwardly below the magnet 41. 65 An armature 45 is also fixed to the free end of the spring 43 to co-act with the electromagnet 41. Pivoted to the lower end of the arm 44 is a second arm 46 having a beveled end 47 extended forwardly. This 70 arm 46 is normally held in a substantially horizontal position by means of a spring 48, fixed to the arm 44 and engaging the arm 46 on its upper side, and a stop 49 to limit its downward movement. Pivotally supported, adjacent to the arm 46, is a switch lever 50 having a rearwardly extending arm 51 carrying a roller 52. The upper end of the lever 50 is beveled at 53 and a contractile coil spring 54 is pivoted 80 to the lower end of the lever 50 and extends upwardly and is attached at its upper end to the support 42. This spring is so arranged that when the lever 50 is in the position shown in Fig. 3, it will yieldingly 85 hold the rear end of the arm 51 downwardly and when the lever 50 is moved to the position shown in Fig. 4 on said spring, it will yieldingly hold the arm 51 upwardly. The spring 58, in the path of the roller 90 52, limits the forward movement of the upper end of the lever 50 and the pin 54^a limits the rearward movement of the upper end of the lever 50. This rearward movement of the lever 50 must be limited by 95 a pin, so that, when the key is finally released, the arm 46 will snap back beyond the lever 50 and assume the position shown in Fig. 3. A set screw 55 carried by the arm 63, is provided for the purpose of 100 adjusting the point of contact between it and the upper end of the arm 50, with reference to the forward movement of the universal bar.

105 Fixed to a support 56 are two contact springs 57 and 58 insulated from each other and extended forwardly, with their forward ends adjacent to each other and normally held just out of contact. The roller 52 stands immediately below the spring 58; 110 hence when the lever 50 is in the position shown in Fig. 4, the roller 52 will hold the contact spring 58 against the contact spring 57, but when the lever 50 is in the position shown in Fig. 3, the contact between the 115 said springs is broken. The power magnet as shown in the diagram, is included in a circuit with this circuit-breaking device comprising the springs 57 and 58, hence when these springs 57 and 58 are in engagement the power magnet will be energized.

120 Pivotaly supported below the power magnet are the arms 59 which support the power armature 60, adjacent to the power magnet 61. The link 62 connects the power 125 armature 60 with the universal operating bar 38 and an arm 63 on this link is extended upwardly and supports the set screw 55.

The arm 63, instead of being upon, and a part of the link 62, may be attached rigidly to, and extend upwardly from one of the arms 37.

- 5 The practical operation of this switch device is as follows: Assuming that the parts are in the position shown in Fig. 3, then upon the completion of a current through the switch magnet 41, the arm 46 will be 10 moved forwardly. This arm is in engagement with the upper end of the lever 50. This upper end will then be moved forwardly by the arm 46 until the upper end of the lever 50 passes forwardly beyond the 15 spring 54, whereupon the said spring will tend to move the upper end of the arm 50 to its forward limit. When the lever 50 is in the position shown in Fig. 4, the circuit-closing springs 57 and 58 are in engagement 20 and the power magnet is energized. As soon as the power magnet is energized the armature 60 will be moved to it and this will move the universal operating bar and the arm 63 rearwardly, the set screw on the latter pressing against the upper end of the lever 50 until it passes the spring 54, whereupon the spring will move it to its rearward limit. The upper end of the arm 50 may move rearwardly before the arm 46 is so 30 moved; for, if the arm 46 is still held in its forward position by the magnet 41, the upper end of the arm 50 will be moved rearwardly and under the arm 46, the spring 48 allowing the latter to move upwardly 35 slightly to permit the return of arm 50 to the position shown in Fig. 3. The better to accomplish this, it is desirable that, at the point where the upper end of the lever 50 passes forwardly beyond the spring 54, the 40 arm 46 shall not quite have completed its full stroke or forward motion. If the upper end of the arm 50 should move rearwardly before the arm 46 is so moved, then when the key is released, the arm 46 will move rearwardly and then engage the upper end of the lever 50. Hence it does not matter whether the arm 46 moves rearwardly before or after the rearward movement of the upper end of the lever 50. It will be seen that moving the 45 upper end of the lever 50 rearwardly releases the spring 54 from holding the contact springs 57 and 58 together, and that by adjusting the set screw 55 the time for thus moving the lever 50, and so breaking the 50 power circuit, with reference to the progress of the type bar stroke, may be regulated.

- It is obvious that only a very slight amount of power is necessary for actuating the circuit-making and breaking spring 58; 60 hence all of the parts connected with this switch device may be of light weight and of small size, and inasmuch as the movement of these parts is very limited there will be comparatively no noise attendant upon their op-

eration and the wear on said parts will be of a minimum amount.

In the electric diagram illustrated in Fig. 2, the battery or other source of electric supply is indicated by the numeral 65. The wire 66 leads from the battery and is electrically connected to each of the conductor rods 16. A conductor wire 67 is connected to each of the contact springs 15 and leads to one of the selective magnets 26. A wire 68 is connected to each selective magnet and 70 also to the relay magnet 41. I also preferably provide a condenser 69 between the wires 68 and 66 to prevent sparking at the key contacts. A wire 70 leads from the relay magnet to a return wire 71 connected to 80 the battery 65. For the power magnet a second circuit is formed consisting of a wire 72 connected to the wire 66 and leading to the power magnet and a wire 73 connected to the power magnet and also connected to 85 the switch springs 57 and 58 and communicating also with the return wire 71. I also preferably provide a condenser 74 in the circuit between the wire 73 and the wire 71 to prevent sparking between the springs 57 90 and 58.

In connection with the carriage shifting device 13, before described, I have provided for operating it by means of a lever 13^a, pivotally supported and arranged in the path 95 of the power armature so that when the power armature is moved toward the power magnet, the lever 13^a will be operated. Pivotated to the top of said lever is a link 13^b, the other end of which is connected to an arm 100 13^c on the upright rock shaft 13^d, which latter is connected to, and designed to operate the ordinary carriage shifting mechanism 13.

The operation of the electrical circuits are substantially as follows: When the contact is made at a key, the corresponding selective magnet and the relay magnet which are connected in a series will be energized at substantially the same time. As soon as the switch device is moved to close the circuit making and breaking springs of the power magnet circuit, the said power magnet is energized and the operation of performing a type bar movement is completed.

Having thus described the construction and operations of each of the various sub-combinations of elements in turn, it is believed that the operation of the machine, as a whole will be readily and easily understood.

It is obvious that by means of my improved construction, the completion of a single electric contact with any key will cause the machine to complete a type bar movement and to return all of the operative parts 125 to normal position. It is obvious further that the mechanical operations of the machine, aside from the type bar movement,

are extremely simple and may be carried on substantially noiselessly and with a minimum of friction and wear. Furthermore, the parts are of simple construction and may 5 be readily and easily assembled or detached.

I claim as my invention:

- the keys, the selective magnets, and the relay magnet are included, type bars, type bar operating devices, a power magnet, an armature for the power magnet, means for operatively connecting the power armature with the type bars, an electric circuit in which the power magnet is included, and a switch device comprising a spring actuated armature for the relay magnet, a pivoted arm yieldingly connected with said relay armature, a pivotally supported switch lever having one end in position to be engaged by said arm, a circuit making and breaking device included in the circuit with the magnet, an arm carried by the switch lever for operating said circuit making and breaking device, an arm connected with the power armature for moving the switch lever to position for breaking the circuit and a spring applied to the switch lever for yieldingly holding the switch lever at either limit of its movement.
11. In an electrically operated typewriter, the combination of keys, selective magnets, a relay magnet, an electric circuit in which the keys, the selective magnets, and the relay magnet are included, type bars, type bar operating devices, a power magnet, an armature for the power magnet, means for operatively connecting the power armature with the type bars, an electric circuit in which the power magnet is included and a switch device comprising a spring actuated armature for the relay magnet, a pivoted arm yieldingly connected with said relay armature, a pivotally supported switch lever having one end in position to be engaged by said arm, a circuit making and breaking device included in the circuit with the magnet, an arm carried by the switch lever for operating said circuit making and breaking device, an arm connected with the power armature for moving the switch lever to position for breaking the circuit, a spring applied to the switch lever for yieldingly holding the switch lever at either limit of its movement, and an adjustable stop device carried by the arm connected with the power armature to engage the switch lever.
12. In a device of the class described, the combination of keys, a series of selective magnets electrically connected with the keys, type bars, type bar operating levers pivoted to a bearing shaft and each operatively connected to a type bar, a universal operating bar, a hook-bearing lever pivoted to each of said type bar operating levers and designed to engage said universal bar, an armature for each of said selective magnets, a pivoted rod operatively connecting each of said armatures to a corresponding hook-bearing lever, said parts being so arranged that when a selective armature has been attracted to its magnet, the pivotal point of said rod

will be brought close to the pivotal point of 65 the type bar operating lever.

13. In a device of the class described, the combination of keys, a series of selective magnets energized upon a depression of the keys, type bars, type bar operating levers, 70 a universal operating bar, a hook bearing lever pivoted to each of said type bar operating levers and designed in one position to engage said universal bar, an armature for each selective magnet, and a link connected 75 to each of said armatures and to a corresponding hook bearing lever, the pivotal point of said links with the armatures being arranged close to the pivotal points of said type bar operating levers for the purposes 80 stated.

14. In an electrically operated typewriter, the combination of keys, selective magnets for the keys arranged to be energized upon the depression of a key, a power magnet, a 85 switch device between the selective magnets and the power magnet designed to close the circuit of the power magnet and to keep it closed until it is automatically opened during the progress of the type bar stroke, and 90 type bars capable of being operated by the said power magnet when the latter is energized whereby the full type bar stroke is insured even though the contact at the key be not long enough to fully energize the 95 power magnet, said switch also being designed to permit the return of the type bar even though the contact at the key continues.

15. In an electrically operated typewriter, the combination of keys, a series of selective 100 magnets electrically connected with the keys, type bars, a bearing shaft, a series of type bar operating levers pivoted to said bearing shaft and each operatively connected with a type bar, a universal operating bar, a power magnet for operating the same, a hook bearing lever pivoted to each of said type bar operating levers and designed to engage said universal bar, an armature for each selective magnet, and a 105 pivoted link for operatively connecting each of said hook-bearing levers to a corresponding armature.

16. In an electrically operated typewriter, the combination of keys, a series of selective 115 magnets electrically connected with the keys, type bars, a power magnet for operating the type bars, means for energizing the power magnet upon a depression of the key, an armature for the power magnet, and 120 a circuit breaking device automatically operated upon a movement of said power armature for breaking the circuit of the power magnet.

17. In an electrically operated typewriter 125 having selective magnets for moving type bar devices to position to be operated and a power magnet for moving the selected

type bar device to printing position, the combination of keys, means operated upon the closing of an electric circuit at a key for establishing a circuit through the power 5 magnet, and means operated by the power magnet for breaking its own circuit during the progress of the type bar stroke.

18. In an electrically operated typewriter, the combination of keys, type bars, type bar 10 operating devices, a power magnet, an armature therefor, means operated upon the depression of a key for operatively connecting a corresponding type bar operating device with the power armature, an electric 15 circuit for the power magnet, a circuit making and breaking device therefor, means also operated upon the depression of a key for moving the said device to close the said circuit, means independent of the key for 20 maintaining the said device in closed position during the progress of a type bar stroke, and means operated by the power magnet for moving the said device to break the said circuit.

25 19. In an electrically operated typewriter, the combination of keys, type bars, a power magnet for operating the type bars, an electric circuit for the power magnet, a circuit making and breaking device for the said 30 circuit, a spring for maintaining the said device in open or closed position, means operated upon the movement of a key for moving the said device to closed position, and means operated by the power magnet for 35 moving the said device to open position so as to break the circuit of the said magnet.

20. In an electrically operated typewriter, the combination of keys, type bars, a power magnet for operating the type bars, an electric 40 circuit for the power magnet, a magnet designed to be energized upon the depression of a key, means operated by the said magnet for closing the circuit of the power magnet, and means operated by the power 45 magnet for breaking the said circuit.

21. In an electrically operated typewriter, the combination of keys, type bars, selective magnets, means for establishing an electric circuit through a selective magnet upon the 50 depression of a corresponding key, a type bar operating device for each type bar, means actuated by a selective magnet, upon the completion of a circuit through it, for moving a corresponding type bar operating 55 device to operative position, a power magnet, an armature therefor, means operated by the said armature for actuating a type bar operating device when the latter has been moved to operative position, means 60 for also establishing an electric circuit through the power magnet upon the depression of a key, and means operated by the power magnet for breaking the said circuit.

22. In an electrically operated typewriter,

the combination of keys, type bars, selective 65 magnets, means for establishing an electric circuit through a selective magnet upon the making of an electrical contact at a corresponding key, a type bar operating device for each type bar, means actuated by a selective magnet, upon the completion of a circuit through it, for moving a corresponding type bar operating device to operative position, a power magnet, an armature therefor, means operated by the said armature for actuating a type bar operating device when the latter has been moved to operative position, a universal magnet energized upon and by the completion of a circuit through any selective magnet, an armature therefor, means 70 operated by the said armature for closing a circuit through the power magnet, and means for automatically breaking the said circuit, irrespective of the breaking of the circuit through the selective magnet, upon a 75 movement of the power armature toward its magnet.

23. In an electrically operated typewriter, the combination of keys, type bars, a type bar operating device for each type bar, means actuated upon the depression of a key for moving a corresponding type bar operating device to operative position, a power magnet, an electric circuit therefor, an armature for the power magnet, means operated 90 by the said armature for actuating a type bar operating device when the latter has been moved to operative position, a circuit making and breaking device for the power magnet, means also actuated upon the depression of a key for moving the said circuit making and breaking device to close the circuit of the power magnet, a device for maintaining said circuit making and breaking device in closed position, and means actuated 100 upon a movement of the power armature toward its magnet for releasing the said holding device from its said action, said means including an adjustable element for regulating the time for releasing the said holding device with reference to the progress of the type bar stroke.

24. In an electrically operated typewriter, the combination of keys, type bars, pivoted type bar operating levers, each operatively 115 connected with a type bar, a universal operating bar, a power magnet for operating the said bar, an electric circuit for the power magnet, hook bearing levers each pivoted to one of the said type bar operating levers and designed to engage the said universal operating bar, pivoted levers, pivoted links for operatively connecting each of the last named pivoted levers with a corresponding hook bearing lever, means operated upon the movement of a key for moving one of the last named pivoted levers so as to cause the corresponding hook bearing lever to engage 120 125

the universal bar, and means also operated upon the movement of a key for closing the circuit of the power magnet.

25. In an electrically operated typewriter, 5 the combination of keys, type bars, a universal operating bar, a power magnet for operating the said bar, an electric circuit for the power magnet, a series of pivoted levers each operatively connected with a type bar, 10 a second series of pivoted levers each operatively connected with one of the first series of levers, a series of hook bearing levers each pivoted to one of the said second series of

pivoted levers and designed to engage the universal operating bar, means operated 15 upon the movement of a key for causing a corresponding hook bearing lever to engage the universal operating bar, and means also operated upon a movement of the key for closing the circuit of the power magnet. 20
